UNITED STATES PATENT OFFICE.

EDWIN H. NELSON, OF DETROIT, MICHIGAN.

DESIGN FOR A BOTTLE.

SPECIFICATION forming part of Design No. 34,372, dated April 16, 1901.

Application filed March 5, 1901. Serial No. 49,978. Term of patent 14 years.

To all whom it may concern:

Be it known that I, EDWIN H. NELSON, a citizen of the United States, residing at Detroit, in the county of Wayne and State of Michigan, have invented and produced a certain new and original Design for a Bottle, of which the following is a specification, reference being had therein to the accompanying drawings, in which—

10 Figure 1 is a perspective view, and Fig. 2 is a plan.

A is the body of the bottle, which in general form is semi-octagonal. In detail the body is provided with a flat side *a* of nearly the greatest width of the base, two sides *b* and *c*, slightly flaring from the side *a*, and three sides *d*, *e*, and *f*, the latter being parallel to the side *a* and arranged centrally between the sides *d* and *e*, which are at an angle thereto. The sides *d* and *e* are roughened by a series of

sides and the adjacent sides are provided with rounded beads *h*, *i*, *j*, and *k*.

The neck of the bottle *B* is cylindrical, having the head *l* at the top of a diameter equal substantially to the distance between the sides *a* and *f*.

The leading feature of the design consists in the body of substantially semi-octagonal form, having the sides adjacent to the front face provided with roughened surfaces and the corners of the meeting sides being provided with rounded beads.

What I claim as my invention is—

The design for a bottle, substantially as herein shown and described.

In testimony whereof I affix my signature in presence of two witnesses.

EDWIN H. NELSON.
